UNITED STATES PATENT OFFICE.

FRANK C. WATKINS, OF PHILADELPHIA, PENNSYLVANIA, ASSIGNOR, BY MESNE ASSIGNMENTS, TO THE UNITED STATES KROTOPHONE COMPANY, OF NEW YORK, N. Y.

TELEPHONE-TRANSMITTER.

SPECIFICATION forming part of Letters Patent No. 355,426, dated January 4, 1887.

Application filed April 27, 1886. Serial No. 200,373. (No model.)

To all whom it may concern:

Be it known that I, FRANK C. WATKINS, a citizen of the United States, residing at Philadelphia, in the county of Philadelphia and State 5 of Pennsylvania, have invented certain new and useful Improvements in Telephone-Transmitters; and I do declare the following to be a full, clear, and exact description of the invention, such as will enable others skilled in the art 10 to which it appertains to make and use the same, reference being had to the accompanying drawings, and to the letters and figures of reference marked thereon, which form a part of this specification.

15 My invention has relation to a telephone-transmitter of peculiar construction, and I have shown it in connection with a telephone of that class wherein the receiver is detachably secured to the transmitter when not in use, and removed therefrom when about to operate, whereby when not in use the battery, transmitter, and receiver are cut out, so that the line runs only through the call-bell to the ground, and when the receiver is detached 20 from the transmitter the call is cut out and the line runs through the secondary circuit of the transmitter, thence through the receiver to the ground, and at the same time the primary circuit is closed in the transmitter; and 25 the object of the invention is to simplify telephonic communication, so that all the subscriber has to do is to detach his receiver from the transmitter when he desires to talk, and to replace it when he is through; and the novelty 30 consists in a transmitter of novel construction, as will be hereinafter more fully described, and particularly pointed out in the claim.

In the accompanying drawings the same letters of reference indicate the same parts of the invention.

Figure 1 is a perspective view of my transmitter and receiver as they appear when not in use. Figs. 2 and 3 are similar views showing the receiver detached from the transmitter when in use. Fig. 4 is a rear elevation of the transmitter, showing the position of the

switches when the receiver is in place. Fig. 5 is a vertical section of the transmitter. Fig. 6 is a detached view of the diaphragm and 50 carbon electrode and manner of mounting the same. Fig. 7 is a modification of the manner of mounting the electrode.

A is the transmitter-case, and B the receiver, the two being connected by a flexible 55 conducting-cord, C, containing two or more conductors, the cord shown in the present case being composed of four conductors to correspond to the peculiar form of transmitter used.

The transmitter-case A is provided with a 60 central cylindrical shell, 2, into which the receiver is inserted when not in use, and in the center of this shell is an orifice, 3, through which the voice reaches the diaphragm. The back of the diaphragm 12 is provided with a 65 platinum button, 4, and against this button rests the oblique-beveled end of the carbon electrode 5, it being supported in a metallic sleeve, 6, provided with an arm, 7, by means of which it is hinged to the depending 70 bracket 8, secured to the interior case, A.

The set-screw 9 in the sleeve 6 permits an easy adjustment of the electrode 5 with reference to its length, and at the same time insures an electrical connection, and the adjustment 75 of the gravity of the electrode is provided for by means of the set-screw 10, the head 11 of which is accessible from the front of the transmitter.

Having thus described my invention, what I 80 claim is—

The combination, with the diaphragm 12, having platina button 4, of the carbon electrode 5, mounted in sleeve 6, provided with arm 7, suspended from the bracket 8, the latter being adjustable by the screw 10, whereby the gravity of the electrode will be varied with reference to the diaphragm, as set forth.

In testimony whereof I affix my signature in presence of two witnesses.

FRANK C. WATKINS.

Witnesses:

H. J. ENNIS,
JNO. N. OLIVER.
